J. ORTIZ.
INCENDIARY BALL.
APPLICATION FILED APR. 7. 1917.

1,294,150.

Patented Feb. 11, 1919.

FIG. 1.

FIG. 2.

WITNESS:

Prof. W. Kitchell.

INVENTOR

Julien Ortiz
BY
Frank D. Bussa
ATTORNEY.

UNITED STATES PATENT OFFICE.

JULIEN ORTIZ, OF GREENVILLE, DELAWARE.

INCENDIARY BALL.

1,294,150.

Specification of Letters Patent. Patented Feb. 11, 1919.

Application filed April 7, 1917. Serial No. 160,342.

To all whom it may concern:

Be it known that I, JULIEN ORTIZ, a citizen of France, residing at Greenville, county of New Castle and State of Delaware, have 5 invented a new and useful Improvement in Incendiary Balls, of which the following is a full, clear, and exact description, reference being had to the accompanying drawings, which form a part of this specification.

10 The object of my invention is to provide a combustible article which, when ignited, will burn vigorously for a substantial length of time.

15 The invention comprises a porous combustible body, impregnated with solidified inflammable material. The invention also comprises such a body provided with a wick impregnated with an inflammable material,

20 which may be such that the wick will ignite when set on fire by contact with a spark or flame or upon exposure to heat, but which is preferably such that it will ignite when exposed to air or by concussion.

25 The substances that may be employed for the combustible body, for the body impregnating material, for the wick, and for the wick impregnating material, are quite numerous. The selection of substances will 30 vary with their availability, their expense and the use for which the article is designed, and may be determined by other considerations.

35 The article is adapted for widely different uses, but will probably be of greatest value and importance when used as a military weapon. Large numbers of them may be carried by aerial vessels and dropped over large areas in which there are inflammable materials such as ripe crops in the field, in stacks, dry leaves, and dry grasses on the ground, and in general any materials

40 easily set afire.

In order that those skilled in the art may 45 manufacture the article without the necessity of experimentation, I shall describe one preferred way of manufacturing the same, in connection with which I shall refer to the accompanying drawings, wherein:—

50 Figure 1 is a perspective view of one form of the article.

Fig. 2 is a view of an apparatus which may be used to impregnate the wick.

I prefer to use straw or similar cheap 55 vegetable fiber and convert it into cellulose

by well known chemical and mechanical operations.

The resultant body *a* will be both combustible and porous, as distinguished from an incombustible porous body such as brick, 60 stone or asbestos.

The combustible body may then be saturated with paraffin or other similar combustible material which will solidify, as distinguished from combustible material which 65 will remain liquid, as, for example, gasolene, kerosene, alcohol, fuel oil and crude oil, of which there may be either evaporation or dropping. Certain other solidifying combustible materials, however, may be found 70 available, if the article is used as a military weapon and provided there is attached thereto the wick saturated as hereinafter described.

The shape of the body is immaterial, but 75 it is preferred to make it of spherical shape, as shown.

For most uses it is advisable or necessary to apply to the body a wick *b*. This wick need not be attached in any particular way, 80 but I prefer to form a hole through the body and pass the wick through the hole so that it will extend from opposite sides of the body and may readily be ignited.

The wick may be saturated with material 85 similar to that of the impregnating material for the porous body. Any readily inflammable material will serve for certain purposes. I prefer, however, especially when the article is intended for warfare, 90 to saturate it with a material which will ignite after a short exposure to the air, and for this reason, I prefer to employ phosphorus.

95 Phosphorus being an inflammable product when in contact with atmospheric air, I dissolve it in a solvent, preferably carbon bisulfid. I dip each wick in succession in the solution, and as soon as dipped I put the balls in a holder intended to contain them. 100 When the holder is filled I put on the lid. A suitable apparatus for containing the balls is set forth in an application filed by me on April 7, 1917, Serial No. 160,343 and need not be herein described, as it forms no 105 part of the present invention.

Fig. 2 shows an apparatus for dipping the wick in the solution of dissolved phosphorus. I have found it practicable to provide a reservoir *d*, containing a mixture of 110

phosphorus and carbon bisulfid, connected, by a pipe *e*, with a dipping pan *f*. As soon as the wick is dipped, it is dropped into the container *c*. After the container is filled, 5 it is closed with a tightly fitting lid.

Having now fully described my invention, what I desire to claim and protect by Letters Patent, is:

1. As a new article of manufacture, a 10 solid body of porous combustible material impregnated with inflammable material, and a wick attached to the body and impregnated with a substance which, upon exposure to air, will ignite and with a volatile 15 liquid which, until free exposure to air, will prevent the ignition of said inflammable substance.
2. As a new article of manufacture, a solid body of porous combustible material impregnated with solidified inflammable material and a wick attached to the body and impregnated with a substance which, upon exposure to air, will ignite and with a vola- 20

tile liquid which, until free exposure to air, will prevent the ignition of said inflammable 25 substance.

3. As a new article of manufacture a solid body of porous combustible material impregnated with inflammable material, and a wick attached to the body and impregnated 30 with phosphorus and carbon bisulfid.

4. As a new article of manufacture, a solid body of porous combustible material impregnated with solidified inflammable material and a wick attached to the body 35 and impregnated with phosphorus and carbon bisulfid.

5. As a new article of manufacture, a cellulose body impregnated with paraffin and a wick attached to the body and impregnated 40 with phosphorus and carbon bisulfid.

In testimony of which invention, I have hereunto set my hand, at Greenville, Delaware, on this third day of April, 1917.

JULIEN ORTIZ.
